(57) **CLAIM**

The ornamental design for a windjammer for camera, as shown and described.

DESCRIPTION

FIG. 1 is a bottom perspective view of a windjammer for camera showing our new design;

FIG. 2 is a another bottom perspective view thereof; and, FIG. 3 is a right side perspective view thereof.

The broken lines in the drawings are for the purpose of illustrating portions of the windjammer for camera that form no part of the claimed design.
